(57) **CLAIM**

The ornamental design for a wall panel for animal pen, as shown and described.

DESCRIPTION

FIG. 1 is a top rear perspective view of a wall panel for animal pen according to the design;

FIG. 2 is a bottom rear perspective view of the wall panel of FIG. 1;

FIG. 3 is a top front perspective view of the wall panel of FIG. 1;

FIG. 4 is a bottom front perspective view of the wall panel of FIG. 1;

FIG. 5 is a rear elevation view of the wall panel of FIG. 1;

FIG. 6 is a front elevation view of the wall panel of FIG. 1;

FIG. 7 is a first side elevation view of the wall panel of FIG. 1;

FIG. 8 is a second side elevation view of the wall panel of FIG. 1;

FIG. 9 is a top plan view of the wall panel of FIG. 1; and, FIG. 10 is a bottom plan view of the wall panel of FIG. 1. The wall panel for animal pen is shown with a symbolic break in its length, the portion of the article between the break lines forms no part of the claimed design.

1 Claim, 9 Drawing Sheets
